(57) **CLAIM**

The ornamental design for an architectural panel with thatch reed design, as shown and described.

DESCRIPTION

FIG. 1 is a front perspective view of an architectural panel portion incorporating the architectural panel with thatch reed design as used in a wall structure;

FIG. 2 is an enlarged view thereof;

FIG. 3 is a front elevational view thereof, the rear elevational view being a mirror image thereof;

FIG. 4 is a left elevational view thereof;

FIG. 5 is right elevational view thereof;

FIG. 6 is a top plan view thereof; and,

FIG. 7 is a bottom plan view thereof.

The broken lines are for illustrative purposes only and form no part of the claimed design.
